(57) **CLAIM**

The ornamental design for an air spray gun, as shown and described.

DESCRIPTION

FIG. 1 is a perspective view of an air spray gun showing 1st embodiment of my new design;

FIG. 2 is a front view of FIG. 1;

FIG. 3 is a back view of FIG. 1;

FIG. 4 is an enlarged left view of FIG. 1;

FIG. 5 is an enlarged right view of FIG. 1;

FIG. 6 is a top view of FIG. 1;

FIG. 7 is a bottom view of FIG. 1;

FIG. 8 is a perspective view of an air spray gun showing 2nd embodiment of my new design;

FIG. 9 is an enlarged view of the encircled area 9 of FIG. 1; FIG. 10 is an enlarged view of the encircled area 10 of FIG. 2; and,

FIG. 11 is an enlarged view of the encircled area 11 of FIG. 6.

The broken lines in the figures illustrate portions of the air spray gun that form no part of the claimed design. The dot-dash lines depict the boundaries of the enlarged views and form no part of the claimed design.

1 Claim, 11 Drawing Sheets
